ATTORNEY

UNITED STATES PATENT OFFICE.

WILLIAM WHEELER, OF BROOKLYN, NEW YORK.

ELECTRICAL FUEL-VAPORIZER.

1,264,724.

Specification of Letters Patent. Patented Apr. 30, 1918.

Application filed June 28, 1917. Serial No. 177,046.

To all whom it may concern:

Be it known that WILLIAM WHEELER, a citizen of the United States, and resident of the borough of Brooklyn, in the county of 5 Kings and State of New York, has invented certain new and useful Improvements in Electrical Fuel-Vaporizers, of which the following is a specification.

This invention relates to means for vaporizing liquid fuel for use in internal combustion motors, and it comprehends means enabling electrical current, in conjunction with a resistor element, to furnish the desired heat whereby liquid fuel, in its passage to 10 the manifold or engine intake, may be raised in temperature and gasified. In practising my invention I have placed the resistor in the passage between the carbureter and the engine, whereby the mixture of fuel and air 15 20 which issues from the carbureter is caused to traverse a heat passage, in order that in such transit the fuel and air may become thoroughly mixed through the action of heat in volatilizing the fuel. The fuel conducting device, which may also support the resistor, may be divided up into a number of small ducts, each containing a resistor strand or length, in order that the volume 25 30 of mingled fuel and air passing through each of these ducts may be relatively small, to permit a more thorough penetration of the passing fuel charge by the heat generated. Also by means of a rheostat or other devices for varying the amperage, I am enabled to regulate the degree of heat generated in the resistor, and thus to govern the developed temperature according to the requirements.

Preheating means for hydrocarbon mixtures, while well known in gas engine practice, have hitherto been limited to service in jacketing the carbureter, or the pipe leading therefrom to the engine, and have not been capable of communicating heat from within 45 the volume of mixture in what may be termed the critical point of its flow, which is just before the fuel enters the engine, to prevent a fall in temperature in the travel of the fuel from the carbureter to the engine. 50 By preheating means such as are comprised in my invention, gasolene may be rendered more serviceable than otherwise, and heavier hydrocarbons, such as kerosene and alcohol, may be generated into gas and 55 also thoroughly blended with their attend-

ant quotas of air, to thus enter the cylinder as an efficient explosive mixture.

Other features and advantages of my said invention will hereinafter appear.

In the drawing:

Figure 1 is a sectional view showing a portion of an engine manifold, in connection with a carbureter, and illustrating a form of my improved electrical vaporizer; and Fig. 2 is a horizontal section on the line 2—2 of Fig. 1.

In the example of my invention shown in the drawing, let 1 indicate a conventional form of a carbureter, and 2 a portion of piping or passage, which may represent a pipe leading directly to the engine intake, or 60 may form a part of an engine manifold. Within the passage 2 I have shown a form of vaporizing device 3, represented as the frustum of a cone, which tapers in the direction 65 of the engine intake, and whose base is provided with a flange 4 that is seated between the respective flanges 5 and 6 of passage 2 and carbureter 1, being secured thereto 70 as by bolts 7. In this or other suitable manner the vaporizer may be localized in operative relation with the carbureter to gasify 75 the mixture flowing to the engine.

The vaporizer 3 is shown as provided 80 with a series of lengthwise arranged apertures 8 which serve the purpose of dividing up the mixture into a number of small columns, said lengthwise apertures also having a series of laterally or radially communicating orifices which extend therefrom to the 85 outer surface of the vaporizer toward the inner or tapering end thereof. Thus the mixture, which is changed to a gaseous state 90 in the vaporizer, issues both from the lengthwise apertures and from the lateral orifices 95 as gas in its passage to the engine. The lateral orifices serve the purpose of providing a more free flow of the formed gas, whose efflux is expedited in this manner.

The conical form of the vaporizer, in co-operation with the cylindrical form shown 100 of the passage 2, affords an increasing area between these members in the direction of the increased expansion, by 105 civilization of the mixture, and is thus conducive to the freedom of flow of the gas.

The heating element within the vaporizer 110 is indicated as a resistor or resistance conductor 9, which is disposed within the apertures 8, it being here shown as threaded to

and fro through the series of said apertures, and its terminals secured in binding posts 10 where it is included in an electrical circuit 11, having a source of electrical energy 12.

5 The resistor strands or lengths within the apertures 8 are suitably insulated from each other, as by constituting the vaporizer device of material which is a non-conductor of electricity. Said resistor strands or lengths, 10 which lie within the series of apertures 8, obviously must not fill said apertures, because clearance is required within the apertures for the passage of the fuel.

Variation of temperature generated in 15 the vaporizer is desirable and may depend in degree upon the temperature of the atmosphere or the character of the fuel in use, and I therefore provide current regulating means such as a rheostat 13, whereby the 20 heat to be generated may be controlled.

I have found in practice that by heating 25 the resistor to incandescence, and presenting its strands or lengths to contact with the fuel passing through the vaporizer device, 30 said fuel, which may have left the carbureter in atomized condition, become vaporized and thoroughly blended with the air in which it is suspended; the device serving in fact as a combined mixing chamber and vaporizer.

Variations may be resorted to within the spirit and scope of my said invention, and parts thereof used without others.

I claim:—
35 1. A vaporizing device of insulating material to be located within the manifold of

an internal combustion engine, and spaced therefrom, said device having a series of lengthwise apertures for fuel flow, a continuous resistor threaded back and forth through said apertures, and an electrical circuit therefor, whereby the temperature of the passing fuel may be raised. 40

2. A vaporizing device to be located within the manifold of an internal combustion engine, and spaced therefrom, said device having a series of lengthwise apertures for fuel flow, each surrounded with insulating material, a continuous resistor threaded back and forth through said apertures, and an electrical circuit therefor, whereby the temperature of the passing fuel may be raised. 45

3. A conical vaporizing device to be located within the intake manifold of an internal combustion engine, and spaced therefrom, said device having a series of lengthwise insulated apertures for fuel flow, and a series of radial orifices arranged toward the tapering portion of said device, a resistor threaded back and forth through said lengthwise apertures, and an electrical circuit therefor, whereby the temperature of the passing fuel may be raised. 50

Signed at the borough of Manhattan in 55 the city, county and State of New York this 21st day of June A. D. 1917.

WILLIAM WHEELER.
